UNITED STATES PATENT OFFICE

148,385

DESIGN FOR A LADDER STAND

Edward F. Paulus, Detroit, Mich.

Application August 9, 1946, Serial No. 132,378

Term of patent 14 years

(Cl. D15—8)

To all whom it may concern:

Be it known that I, Edward F. Paulus, a citizen of the United States, residing at Detroit, in the county of Wayne and State of Michigan, have invented a new, original, and ornamental Design for a Ladder Stand, of which the following is a specification, reference being had to the accompanying drawing, forming part thereof.

In the drawing

Fig. 1 is a perspective view of a ladder stand, showing my new design;

Figure 2 is a plan view of the same;

Figure 3 is a front elevation of the same; and

Figure 4 is a vertical cross section taken on a plane indicated by the line 4—4 in Figure 2.

I claim:

The ornamental design for a ladder stand, as shown.

EDWARD F. PAULUS.
